(57) **CLAIM**

The ornamental design for a set of aircraft canards, as shown and described.

DESCRIPTION

FIG. 1 is a left side plan view of the set of aircraft canards; FIG. 2 is a right side plan view of the set of aircraft canards; FIG. 3 is a front plan view of the set of aircraft canards; FIG. 4 is a right front elevated isometric view of the set of aircraft canards; and,

FIG. 5 is a top plan view of the set of aircraft canards. The broken line showing of the aircraft is for the purpose of illustrating the environmental structure in which the claimed elements are found and forms no part of the claimed design. In addition, thick lines are used to outline objects, while thin lines show contours.
